UNITED STATES PATENT OFFICE.

JULIUS RITTER, JR., OF RACINE, WISCONSIN, ASSIGNOR TO HARTMANN TRUNK COMPANY, OF RACINE, WISCONSIN, A CORPORATION OF WISCONSIN.

TRUNK CONSTRUCTION.

Application filed October 22, 1923. Serial No. 670,060.

To all whom it may concern:

Be it known that I, JULIUS RITTER, Jr., a citizen of the United States, and resident of Racine, in the county of Racine and State 5 of Wisconsin, have invented new and useful Improvements in Trunk Constructions, of which the following is a description, reference being had to the accompanying drawings, which are a part of this specification.

10 This invention relates to improvements in trunk construction.

Wardrobe trunks of the better class now on the market are adapted to stand on end and are divided vertically into two sections 15 to form a wardrobe section and a drawer section, the drawer section usually having an open upper end closed by a hinged cover. The joints formed by the sections and cover are usually covered by the ordinary valance 20 strip and therefore do not exclude dust and other foreign matter.

It is one of the objects of the present invention to overcome the above objectionable features and provide a construction in which 25 the valance members, the dowel fittings and hinges are combined to produce a dust tight trunk joint.

A further object of the invention is to provide a dust proof trunk in which the valance 30 members, the dowel fittings and the hinges are all combined in a manner to form continuous strips of metal without joints extending around the abutting edges of the sections and cover.

35 A further object of the invention is to provide a trunk construction which is simple, strong and durable and is well adapted for the purpose described.

With the above and other objects in view, 40 the invention consists of the improved dust proof trunk and its parts and combinations as set forth in the claims and all equivalents thereof.

In the accompanying drawing in which 45 the same reference characters indicate the same parts in all of the views:

Fig. 1 is a perspective view of the improved trunk construction;

50 Fig. 2 is a vertical sectional view of the upper portion of the trunk showing both sections and the top cover;

Fig. 3 is a transverse sectional detail view on a larger scale of one of the hinge portions of the trunk taken on line 3-3 of 55 Fig. 4;

Fig. 4 is a longitudinal sectional detail view of the hinge taken on line 4-4 of Fig. 3;

Fig. 5 is a transverse sectional view of the trunk taken on line 5-5 of Fig. 2; and 60

Fig. 6 is a transverse sectional detail view on a larger scale of one of the dowel portions of the trunk taken on line 6-6 of Fig. 1.

Referring to the drawing, the numeral 8 65 indicates a wardrobe trunk which comprises a drawer section 9, a wardrobe section 10 having an upper open end 11 and a cover 12 for said open end.

The abutting edge portions of the trunk 70 sections and cover are provided with strips of metal 13 which extend parallel to the trunk joint and in parallel relation to each other. These strips are formed with outwardly bulged elongated dowel pins 14 and 75 outwardly bulged elongated recessed portions 15 for receiving said pins in overlapping engagement. Said strips are also formed with outwardly bulged portions forming hinges 16 for connecting the parts 80 together and with locks 17 and 18 for locking the parts in closed position. Adjacent the points of junction between the cover and the two trunk sections the strips are of angular formation and the dowel members 14' 85 and 15 are of angular form to reinforce the parts. The elongated dowel members have rounded end flanges 19 and 20 which reinforce said members to a considerable extent and also exclude the dust from entering the 90 joints, and furthermore, protect the trunk in sliding over surfaces during transportation.

To form smooth rounded outer surfaces of the bulged portions, the dowel pins 14 are 95 offset inwardly forming shoulders 21 which abut against the adjacent edges of the recessed portions 15, as clearly indicated in Fig. 6. Said shoulders also serve as stops to limit the closing position of the parts. 100

From the foregoing description, it will be seen that the construction provides continuous reinforcing members which extend entirely around the end and side portions of the trunk and that said members are shaped 105 and combined in a manner to form dowels and hinges and also to form dust proof joints.

What I claim as my invention is:

1. A trunk construction, comprising 110

trunk sections having meeting edges, and strips of material mounted on side portions of said edges and having portions shaped to form hinges connecting the sections together and having other portions shaped to form elongated dowel pins and dowel pin recesses extending substantially the length of the edges, which are entered by the dowel pins to reinforce the meeting edges of the trunk sections and form a continuous dust proof connection therebetween.

2. A trunk construction, comprising trunk sections having meeting edges, and strips of material mounted on side portions of said edges and having outwardly bulged portions shaped to form hinges connecting the sections together along one side, and also having other outwardly bulged portions shaped to form elongated dowel pins and dowel pin recesses extending substantially the length of the edges, which are entered by the dowel pins to reinforce the meeting edges of the trunk sections and form a continuous dust proof joint therebetween.
25. 3. A trunk construction, comprising trunk sections having meeting edges, and strips of metal mounted on side portions of said edges and having outwardly bulged elongated portions to form hinges connecting the sections together along one side, and also having other outwardly bulged portions shaped to form elongated inwardly offset dowel pins and dowel pin recesses extending substantially the length of the edges, which are entered by the dowel pins to reinforce the meeting edges of the trunk sections and form a continuous dust proof joint therebetween.
30. 4. A trunk construction, comprising trunk

sections having meeting edges, one of said sections having an open upper end closed by a cover having edges which meet the section edges, and strips of metal mounted on side portions of the edges of the sections and cover and having outwardly bulged elongated portions to form hinges connecting the sections together along one side and also the cover to one of the sections, said strips of metal also having outwardly bulged portions shaped to form elongated dowel pins and dowel pin recesses extending substantially the length of the edges, which are entered by the dowel pins to reinforce the meeting edges of the trunk sections and cover and to form continuous dust proof joints therebetween.

5. A trunk construction, comprising trunk sections having meeting edges, one of said sections having an open upper end closed by a cover having edges which meet the section edges, and strips of metal mounted on side portions of the edges of the sections and cover and having outwardly bulged portions to form elongated hinges connecting the sections together along one side and also connecting the cover to the section having a closed upper end, said strips of metal also having outwardly bulged portions shaped to form elongated inwardly offset dowel pins and dowel pin recesses extending substantially the length of the edges, which are entered by the dowel pins to reinforce the meeting edges of the trunk sections and cover and to form continuous dust proof joints therebetween.

In testimony whereof, I affix my signature.

JULIUS RITTER, JR.
